(57) **CLAIM**

The ornamental design for a lighting device, as shown and described.

DESCRIPTION

FIG. 1 is a top front perspective view of a lighting device showing a new design.

FIG. 2 is a bottom rear perspective view of the lighting device of FIG. 1.

FIG. 3 is a front view of the lighting device of FIG. 1.

FIG. 4 is a back view of the lighting device of FIG. 1.

FIG. 5 is a left side view of the lighting device of FIG. 1.

FIG. 6 is a right side view of the lighting device of FIG. 1.

FIG. 7 is a top view of the lighting device of FIG. 1; and,

FIG. 8 is a bottom view of the lighting device of FIG. 1.

The broken lines shown are provided for the purpose of illustrating portions of the lighting device and form no part of the claimed design.

1 Claim, 8 Drawing Sheets
